ELECTRIC PRESSURE INDICATOR

Reginald Cyril Fuller, Brighton, England

Application June 21, 1946, Serial No. 678,261
In Great Britain December 19, 1945

3 Claims. (Cl. 201—51)

1

This invention relates to fluid pressure operated electrical switches adapted to respond to the influence of hydraulic or gaseous fluid pressure for automatically making and/or breaking a circuit for apparatus actuated electrically and having a certain operative relationship with the hydraulic or gaseous fluid pressure generating means or means consuming energy from the source of fluid pressure or converting such pressure into kinetic energy. Or, the switch in one form of the invention may be adapted as a means for controlling the operation of a fluid pressure indicating gauge, signalling device or automatic controlling device.

Fluid pressure operated switches have been proposed heretofore in which a diaphragm exposed to the direct influence of the fluid pressure is deformed, against the influence of a spring by the fluid pressure to actuate contacts. Also the use of a stack of carbons, or a carbon body, in the circuit of a pressure indicating apparatus including an electrically operated pressure gauge has been proposed heretofore in which the pressure generated is transmitted to the carbon stack or body to vary the resistance of the stack or body for producing changes in the indicator of the gauge.

However in such heretofore proposed appliances the diaphragm actuated switching means was not suitable for use where the pressure applied varied over a wide range and consequently if such appliances were used under such conditions the diaphragm would yield beyond its predetermined elastic limit so as to cause the appliance to fail, or the diaphragm to acquire a permanent deformation resulting in the appliance becoming unreliable in operation. Or, in other of the said appliances the diaphragm, which is undesirable, is perforated to receive a contact member and/or it is subjected directly to the action of the spring when the fluid pressure falls below the load of the spring, and consequently is liable to be permanently deformed by the spring.

The object of the present invention is to provide a fluid pressure operated electrical switch incorporating a diaphragm and of sturdy and simple form which is cheap and simple to manufacture and which obviates the aforesaid disadvantages.

According to this invention a fluid pressure operated electrical switch of the type embodying an imperforated diaphragm exposed wholly on one side, with the exception of its clamped periphery to the influence of the fluid pressure to deform it to actuate the switch and in which the

2

switch contacts are isolated from the diaphragm and actuated in one direction by resilient means which yieldingly opposes said deformation of the diaphragm, is characterised in that the said resilient means is an adjustable spring and by the provision therewith of stop means separate from the diaphragm preventing transmission of any or any but a relatively very small portion of the load of said adjustable spring to the diaphragm when the fluid pressure falls below the effective load of the spring, and also by the provision of an overload preventing member forming a positive stop against excessive deformation of the diaphragm beyond that produced by a predetermined minimum of the range of fluid pressure to which the switch is to respond.

In a practical embodiment of the invention, the contacts referred to above also form part of the means for protecting the diaphragm from receiving the full available pressure of the spring when the fluid pressure drops below a predetermined minimum, and they take the form which will positively make or break the desired circuit with a high degree of accuracy immediately the diaphragm has been deformed out of its idle or non-operative normal state to an extent which will ensure the diaphragm reasserting its normal or idle state when the pressure drops below the predetermined minimum without any lag or sticking by the diaphragm such as would arise if the diaphragm were deformed to a point nearer its elastic limit than to its normal or idle state. Contacts for such purpose could take the form of a carbon stack interposed between the said overload preventing member and the spring, the operative connection between the diaphragm and spring being in the form of a stud slidable through the overload preventing member and some of the contacts and making light contact with the diaphragm and a contact member forming with the carbon stack a positive stop for the spring.

In one practical embodiment of the invention the switch comprises a housing with opposed annular surfaces between which is gripped a flexible diaphragm, one of said surfaces being recessed to accommodate the head of a stud abutting against the face of the diaphragm remote from the face exposed to the fluid pressure, said stud sliding through said recessed surface to afford a switch actuating part, said stud head and the surface receiving it acting as an overload stop to prevent overloading of the diaphragm as the fluid pressure rises above a predetermined minimum pressure required to cause the stud to actuate the switch

contacts for making or breaking the desired circuit.

If as aforesaid the contacts are carbon bodies in a carbon stack they may be annular members through which a shank of the stud slides freely, the stud being adapted under the influence of the fluid pressure to overcome the spring applying compression to the carbon bodies, but at fluid pressures below a predetermined minimum being protected by the carbon bodies from receiving any, or any but a relatively very light portion, of the pressure of the spring, whereby there will be an accurate and prompt response of the switch diaphragm to increase of fluid pressure above said predetermined minimum.

In order that the invention may be clearly understood and readily carried into effect, drawings are appended hereto illustrating an embodiment thereof, and wherein,

Figure 1 is a sectional elevation view of a resistance device suitable for incorporation with the lubricating oil circuit of an internal combustion engine.

Figure 2 is a plan view of Figure 1, and

Figure 3 is a diagram showing the connection of the device in the electrical circuit of an electrically operated pressure indicator.

Referring to the drawings, the variable electric resistance embodies a stack of annular carbon rings 1 enclosed in an insulating tube 2, pressure against a contact plate 2 on top of the carbon rings 1 being applied by an adjustable device comprising a coiled compression spring 4 interposed between the top contact plate 3 and a plate 5 carried by an adjusting screw 6, such screw conveniently comprising a terminal to which can be connected one end of a lead 7 from the gauge or signalling device indicated diagrammatically at 8 in Figure 2.

The said insulating tube forms part of, or is accommodated within a housing, which is partitioned into one end portion provided with an adapter or union device 9 for the reception of a pipe, or for attachment to the output of a pump, so that the pressure of the circulating system is transmitted directly to a diaphragm 10. This diaphragm can be metallic, but preferably, by reason of the manner (hereinafter described) in which the diaphragm is protected against excessive deformation and load in both directions along its axis, is composed of a non-porous fabric. The diaphragm is engaged on the side remote from the fluid pressure receiving side by the flanged head 11a of a stud 11 having a shank 11b passing loosely through a bottom contact plate 12, which plate in conjunction with the flanged head 11a affords a positive stop for the diaphragm to prevent overloading of the diaphragm by the fluid pressure. The shank 11b also passes through the stack of carbon rings 1, this stud being of insulating material. It will be seen that displacement of the diaphragm 10 due to the pressure of hydraulic fluid causes the shank 11b of the insulated stud 11 to engage with the top contact plate 3 and thus relieve the stack of carbon rings from the pressure due to the action of the said coiled compression spring 4. Relaxation of the spring pressure on the stack of carbon rings produces a change in resistance which can be recorded by a simple type of indicating meter, or by varying the luminosity of a lamp 13 (see Figure 3), so that the lamp is only illuminated fully when there is no working pressure upon the fluid, or when such pressure drops below a predetermined minimum.

When the device is intended for use in connec-

tion with a lubricating circuit of an internal combustion engine, or for like purposes, the dimensions of the housing 2 can be such that it is merely an inconspicuous fitment to the appropriate part of the apparatus, and for normal requirements the housing 2 can comprise the cylindrical body as shown having an annular flange 2a, the diameter of which need not exceed about one and a half inches, the other body part 9 of the device being likewise flanged as at 9a, the two flanges being coupled together, with the bottom contact plate 12 and diaphragm 10 gripped between them by an annular or gland nut 14 threaded on to the flange 9a. In practice the electrical circuit is completed through the stack of carbon rings 1, e. g. one end ring of the stack 1 being connected electrically to the coil spring via the top contact plate 3 and thereby being electrically connected to the aforesaid pressure adjusting screw 6 and the indicator 8 and the other end carbon ring being connected to the bottom contact plate 12 which can be fitted with a terminal 12a for connection to a battery, or may be directly connected via the union device 9 to earth.

The device is arranged so that the maximum pressure actually breaks the circuit through the carbons after increasing the resistance.

It will be seen from the foregoing that excessive fluid pressure cannot damage the diaphragm 10, by reason of the insulated stud head 11a abutting against the bottom contact plate 12 thereby restricting any further movement of the insulated stud and diaphragm after they have performed the function of varying the resistance and finally breaking the circuit at a predetermined pressure. Also that the diaphragm cannot be ruptured or subjected to undesirable strains by the load of the spring when the fluid pressure against the diaphragm falls below a predetermined minimum, by reason of the stack of carbon ring 1 and contact plate 3 serving as a stop between the member 12 and the spring 4.

I claim:

1. A fluid pressure operated electrical switch comprising a housing, an imperforated diaphragm therein exposed wholly on one side, with the exception of its clamped periphery to the influence of the fluid pressure to deform it to actuate the switch, switch contacts isolated from the diaphragm, resilient means actuating the contacts in one direction and yieldingly opposing said deformation of the diaphragm, said resilient means comprising an adjustable spring, stop means separate from the diaphragm preventing transmission of any, or any but a relatively very small portion of the load of said adjustable spring to the diaphragm when the fluid pressure falls below the effective load of the spring, and an overload preventing member forming a positive stop against excessive deformation of the diaphragm beyond that produced by a predetermined minimum of the range of fluid pressure to which the switch is to respond.

2. A switch according to claim 1 wherein the said contacts are arranged as a stack at least one of which is a carbon member interposed between said overload preventing member and a contact member, said latter member being engaged by the spring, and the overload stop also acting as a contact member and being connected to a terminal, the spring forming an electrical connection across a further terminal and the said contact it engages, a stud slideable through the contacts and having a flanged head resting against the diaphragm and a stem engaging the contact sub-

jected to the spring pressure, the contacts preventing the spring from overloading the diaphragm, when the fluid pressure is below a pre-determined switch operating pressure.

3. A switch according to claim 2 comprising a 5 housing in which are provided opposed annular surfaces between which is gripped the imperforated flexible diaphragm one face of which is adapted to be exposed to the influence of fluid pressure, one of said surfaces being one face of 10 an annular metallic member comprising the overload preventing member and being recessed to accommodate the head of the said stud, such head abutting against the face of the diaphragm remote from the face exposed to fluid pressure, the 15 stem of said stud sliding through said annular member, the said spring being a coiled compression spring interposed between the appropriate contact member and a terminal fitting in the 20 housing provided with means for adjusting the normal load of the spring.
